UNITED STATES PATENT OFFICE

JULIUS TOROK AND EDWIN LEE BERGSTRESSER, OF RENOVO, PENNSYLVANIA

DISCHARGE CHUTE

Application filed February 9, 1932. Serial No. 591,800.

Our invention relates to discharge chutes and more particularly to coal chutes, the invention being especially directed to means for controlling from a remote station the direction and rate of discharge of the material passing through the chute.

The object of the invention, generally speaking, is to provide at the discharge end of a coal chute or the like devices for handily controlling the passage of the material, as to the rate of its flow and direction of its discharge, so arranged and correlated as to reduce breakage of the material to a minimum.

Other more specific objects and advantages characterizing our invention will become more fully apparent from the description hereinafter of one embodiment or example of the practice thereof, the description having reference to the accompanying drawings.

Of the drawings:

Fig. I represents a side elevation of the discharge end of a coal chute embodying our invention.

Fig. II represents an end elevation of the same.

Fig. III represents a plan view of the same.

Fig. IV represents an enlarged detailed view, partly in cross section, showing the worm drive for the gate at the discharge end of the chute.

Fig. V represents diagrammatically the electrical circuits leading to the motor which actuates the bottom gate.

In the drawings, there is illustrated only a portion of the discharge end of a coal chute, and it may be assumed, for example, that the tube section designated at 1 comprises the end section of a common type of telescoping chute supported for swinging movement at a loading or unloading station and controlled from a remote point. In the present example of our invention, the tube section 1 is of rectangular cross section throughout the major portion of its length with the corners cut out near the lower end as shown at 2. At its extreme lower end the tube 1 has fitted thereon a rotatable bucket or elbow extension 3. The bucket 3 is rotated about the tube 1 by means of a large ring gear 4 which meshes with a pinion 5 on a driving shaft 6. The

driving shaft 6 is in turn supported with a bracket 7 attached to the tube section 1 and is driven through bevel gears 8 by a motor 9. The motor 9 is mounted on a bracket 10, also attached to the tube 1.

The tube section 1 and the bucket 3 which rotates about its axis define a passage terminating in a laterally directed discharge opening 11 from which the coal passes from the chute in any desired direction. Adjacent to the opening 11, the bucket 3, which in the present instance is of square cross-section, is provided with a curved deflector plate 12. For opening and closing the opening 11, a gate 13 is pivotally mounted on the bucket 3.

An additional motor 15 is shown for effecting revolution of the gate 13 to open and close the discharge opening 11 the desired amount, and thereby to regulate the quantity or rate of flow of the coal to be discharged.

In order to furnish current for the motor 15 which actuates the gate 13, we preferably provide collector rings 16 in association with the ring gear 4, and brushes 17 in fixed relation to the tube section 1. The collector rings 16 are mounted on the ring gear 4 by means of supports 18 of insulating material. Adjacent to the collector rings 16, the tube section 1 is cut away at the corners as indicated at 2 to afford ample clearance for the collector rings. The brushes 17 are mounted on brush holder studs 19 which are in turn secured to block supports 20 of insulating material bolted to the tube section 1. Directly above the brushes 17 removable covers 21 are provided which render convenient access to the brushes for purposes of adjustment or replacement. A cylindrical guard 22, completely housing the collector rings 16 and extending downward to cover the ring gear 4, is also preferably provided.

The gate 13 is shown with side members 23 substantially in the form of a quadrant of a circle to which a curved bottom plate 24 is riveted. One side member 23 is fitted with a relatively short fulcrum gate pin 25 which is fastened to a bracket 26 secured to the corresponding side of the bucket 3. The bracket 26 is bifurcated to accommodate the side mem-

ber 23 of the gate 13. The other side member 23, which is fitted with a relatively long fulcrum gate pin 27, has welded thereto the hub portion 28 of a worm gear 29. A housing 30 affords a bearing for the fulcrum pin 27 and encloses the worm gear 29, making it dust proof. The housing 30 is secured to a bracket 31 on one side and to the bucket 3 on the other side by means of a flange 32. The bracket 31, which is secured to the side of the bucket 3, includes a flat plate 33 upon which the motor 15 is supported and outwardly projecting arms 34 which afford bearings for the worm shaft 35. Between the arms 34 of the bracket 31 a worm 36 is mounted on the worm shaft 35. The worm 36 meshes with the worm gear 29 and drives the same to revolve the gate 13 about its fulcrum pins 25 and 27. A cover plate 37 encloses the worm 36.

As shown in Fig. IV, the worm shaft 35 is connected to the shaft 73 of the motor 15 by means of a coupling 74. The coupling 74 is splined to the motor shaft 73 by a key 75. At its upper end the worm shaft 35 is fluted as shown at 76 to engage corresponding notches in the coupling 74, and there is thus effected a positive connection between the motor 15 and the worm 36. The coupling 74 serves not only to permit the removal of the worm shaft 36 without removal of the motor 15, but it also relieves lateral and differential motions between the motor shaft 73 and the worm shaft 35. Between the arms 34 of the bracket 31 and worm 36 ball bearings 77 are inserted to take the thrust of the worm.

Between the motor 15 and the worm 36, a magnetic brake 38 is mounted upon the bracket 31. The brake 38 includes brake shoes 39 which are pressed by means of springs 40 against the motor shaft 73. It may be assumed that the brake 38 is of a well-known commercial type including electromagnetic means for withdrawing the brake shoes 39 from the motor shaft 73, against the pressure of the spring 40, when the circuit to the brake is energized.

Upon the ends of the gate 13, projecting lugs 41 are welded or otherwise attached. The lugs 41 are adapted to engage limit bumpers 42 which are secured at opposite sides of the bucket, and which include plungers 43, carrying rollers 44, urged toward the gate lugs 41 by springs 45 within the cylinders 46. As the gate 13 moves to "fully closed" position, as indicated by the dot-and-dash lines of Fig. I, one lug 41 strikes the roller 44 of the bumper 42 shown at the left-hand of the figure, and the force of the impact is absorbed by the spring 45. When the spring 45 is compressed to a predetermined point, the motor 15 is overloaded, and, by means of electrical devices hereinafter described, the circuit of the motor 15 is automatically opened, causing the motor to stop.

Likewise as the gate 13 moves to "fully open" position, the other lug 41 strikes the bumper 42 shown at the right-hand of Fig. I, and causes the motor 15 to become overloaded and to be stopped automatically. In the normal operation of the coal chute, however, the operator reverses or stops the motor 15 before the gate 13 reaches either limit of its travel, and the limit bumpers 42 serve merely as safety devices.

An example of an electrical circuit which may be employed in connection with the motor 15 is shown diagrammatically in Fig. IV. In this example, the motor 15 is represented as a three phase induction motor with conductors 47a, 47b and 47c leading thereto through the collector rings 16, brushes 17, and a junction box 48. In circuit with the main conductors 47a, 47b, 47c, there is shown a line starter S, and a thermal relay T. Push buttons 49, 50 and 51 are shown mounted on a control panel P, and they control respectively the stopping, forward movement and reverse movement of the motor 15. The magnetic brake previously described is represented diagrammatically at 38. Contacts 52a, 52b and 52c of the line starter S are operative in the control of forward movement of the motor 15, whereas contacts 53a, 53b and 53c are operative in the reverse movement of the motor.

The operation of the electrical apparatus is as follows: When the "forward" push button 50, which is normally out of contact, and which is closed against the pressure of a spring, is actuated, a circuit is closed causing current to pass from main line conductor L² through coil 54, conductor 55, the contact at push button 50, conductor 56, including contact 57 of the thermal relay T to L³, thus energizing coil 54, and causing the contacts 52a, 52b and 52c of the line starter S to close. With the "forward" contacts 52a, 52b, 52c of the line starter S closed, current passes from main line conductor L¹, through contact 52a, coil 58 of the thermal relay T to conductor 47a, and thence through collector ring 16 and conductor 72a to the motor 15. Current also passes from main line conductor L² through contact 52b, and conductor 47b, conductor 72b to the motor 15. Current also passes from main line conductor L³ through contact 52c, coil 59 of the thermal relay T, conductor 47c, conductor 72c, and thence to the motor 15.

When the "reverse" push button 51, which is normally out of contact, and which is closed against the pressure of a spring, is actuated, a circuit is closed causing current to pass from main line conductor L² to conductor 60, and thence through coil 61, conductor 62, the contact at push button 51, conductor 56, including contact 57 of the thermal relay T to L³, thus energizing coil 61, and causing the contacts 53a, 53b and 53c of the line start-

er S to close. Coil 54 in the meanwhile has been de-energized by release of the "forward" pushbutton 50, and contacts 52a, 52b and 52c have opened. With the reverse contacts 53a, 53b, 53c of the line starter S closed, current 5 passes from main line conductor L¹ to conductor 63, contact 53a, conductor 64, to coil 59 of the thermal relay T, and thence through conductor 47c and conductor 72c to the motor 15. Current also passes from main line conductor L², through conductor 60, contact 53b, conductor 65, conductor 47b, conductor 72b and thence to the motor 15. Current also 10 passes from main line conductor L³ through conductor 66, contact 53c, conductor 67, to coil 58 of thermal relay T and thence through conductor 47a and conductor 72a to the motor 15. Accordingly, with the "reverse" button 15 actuated, the phases of the motor 15 are 15 reversed and its direction of rotation is 20 changed.

To stop the motor, the "stop" push button 49, which is normally closed is opened. This causes both coil 54 and coil 61 to be deenergized, so that all the contacts of the line 25 starter are opened.

With the motor going in either direction, in case the gate 13 should strike the limit bumper 42 on the bucket 3, the resistance 30 offered to further movement of the gate causes the motor 15 to become overloaded, which in turn causes the coils 58 and 59 of the thermal relay T to become excessively heated, whereupon the temperature responsive elements 67 are caused to flex with resulting movement of the cross arm 68 and contact 69. This opens the contact at 57, and causes the motor to stop automatically. The movement of the cross arm 68 is followed by dropping by gravity of the latch 70, the hooked end of which catches upon the cross arm 68 and maintains the open circuit until the bell cord 71 is actuated, releasing the cross arm 68.

45 Whenever the motor 15 is stopped by reason of the opening of the circuit thereof, current to the magnetic brake 38 is shut off. Its electromagnetic coil is therefore de-energized and the springs 40 cause the brake 50 shoes 39 to press against the motor shaft 35, rapidly retarding further movement of the gate 13.

The control panel P is located at the remote station from which the various movements of the coal chute are controlled, including the operation of the motor 9, which effects rotation of the bucket 3 about the axis of the tube 1. The conductors 47a, 47b, 47c, which lead to the brushes 17, are attached to the tube 1, whereas the other set of conductors 72a, 72b, 72c which lead from the collector rings 16 to the motor 15, are attached to the rotary bucket 3.

In operating the coal chute of this invention, the discharge tube 1 is first positioned

by mechanical apparatus, which forms no part of this invention, at a point above the site where coal is to be dumped. Subsequently, by means of the motor 9, the bucket 3 is rotated about the tube 1, so that its discharge opening 11 is directed laterally of the tube 1 toward the dumping site. Thereupon by manipulation of the push buttons 49, 50 and 51 of the control panel P, the gate 13 is moved back and forth to regulate the flow 70 of coal from the bucket in such manner as to minimize breakage.

It will be particularly noted that the gate 13 in its fully open position is disposed behind the curved deflector plate 12, and that 80 when it is desired to retard the rate of discharge of material, the gate is swung upward towards a position directly in advance of the deflector plate 12. Accordingly, when the discharge chute is operated, and especially when it is desired to reduce breakage to a minimum, the gate is first closed, and when the chute has become filled with material, it is opened gradually, permitting the material to spill out at the side while being retarded in its flow by the deflector plate 12 and a portion of the inner surface of the gate. Thus a sheer drop of the material and the breakage resulting therefrom is avoided. Furthermore, the manner in which the gate 95 is operated greatly facilitates the trimming of the bunker or other receptacle into which the material is discharged. By revolving the bucket 3 with the gate partially opened, the material, instead of pyramiding itself in the bunker in the manner customary with discharge chutes now in common use, is caused to be spread evenly in layers. It will also be observed that when the lower end of the chute is buried in the pile of discharged material, the flow will not be interrupted so long as the opening is not wholly obstructed, and that closure of the gate can be readily effected while the end of the chute is still 100 buried in the pile.

110 While we have described one form which our invention may take, it will be apparent that various changes may be made in the particular apparatus herein illustrated and described without departing from the spirit of our invention. For example, it is contemplated that the particular form or shape of the tube, bucket and gate of our invention may be varied considerably without affecting their mode of operation.

115 Having thus described our invention, we claim:

1. In a discharge chute, a tube, a bucket rotatable about the axis of the tube at the end thereof and terminating in a laterally directed discharge opening, a gate pivoted on said bucket and movable upward to retard the rate of flow of material through said discharge opening, a driving unit mounted on 125 said tube for effecting rotation of the bucket 130

- about said tube, and an additional driving unit mounted on said elbow extension for opening and closing said gate.
2. In a discharge chute, a tube, a bucket rotatable about the axis of the tube at the end thereof and terminating in a laterally directed discharge opening, a curved deflector plate at said opening, a gate pivoted centrally of said bucket and adapted to be revolved upward from a position behind said deflector plate to a position in advance thereof to close said opening, means mounted on said tube for effecting rotation of said bucket, and means mounted on said bucket for revolving said gate.
3. In a discharge chute, a tube, a bucket rotatable about the axis of the tube at the end thereof, a curved deflector plate tangential to the wall of said bucket forming a laterally directed discharge opening, a gate pivoted centrally of said bucket and adapted to be revolved upward from a position behind said deflector plate to a position in advance thereof to close said opening, means mounted on said tube for effecting rotation of said bucket, and means for revolving said gate.
4. In a discharge chute, a bucket forming the terminus of a discharge passage, a gate pivoted on said bucket and adapted to be revolved from one position to another to open and close said discharge passage, a motor for actuating said gate, means adapted to be engaged by said gate as the gate approaches its limits of movement for increasing the load on said motor, and means for opening the circuit to said motor when the load reaches a predetermined point.
5. In a discharge chute, a bucket forming the terminus of a discharge passage, a gate on said bucket adapted to be moved from one position to another to open and close said discharge passage, a motor mounted on said bucket for actuating said gate, means for controlling the direction of said motor, and a magnetic brake for retarding movement of said gate, said brake being automatically applied when said motor is stopped.
6. In a discharge chute, a tube, a bucket rotatable about the axis of the tube at the end thereof, a gate pivoted on said bucket and adapted to be revolved from one position to another to open and close said discharge passage, a motor mounted on said bucket for actuating said gate, a circuit to said motor including means for controlling its direction, starting and stopping, and a magnetic brake for retarding movement of said gate, said brake being automatically applied when the circuit to said motor is opened.
7. In a discharge chute, a bucket forming the terminus of a discharge passage, a gate pivoted on said bucket and adapted to be revolved from one position to another to open and close said discharge passage, a motor for actuating said gate, a relay for opening the circuit to said motor when its load reaches a predetermined point, means coacting with said gate for increasing the load on said motor as the gate approaches its limits of movement, and a brake for retarding movement of the gate, said brake being automatically applied when the circuit to said motor is opened.
8. In a discharge chute, a bucket forming the terminus of a discharge passage, a gate pivoted on said bucket and adapted to be revolved from one position to another to open and close said discharge passage, a motor for actuating said gate, bumpers coacting with said gate for increasing the load on said motor as the gate approaches its limits of movement, and a relay for opening the circuit to said motor when its load reaches a predetermined point.
- In testimony whereof, we have hereunto signed our names at Renovo, Pennsylvania, this 30th day of January, 1932.
- JULIUS TOROK.
